Inventor

John Biro

By his Attorney E. M. Bentley

UNITED STATES PATENT OFFICE.

JOHN BIRO, OF NEW YORK, N. Y.

METAL FORMER.

Application filed September 20, 1924. Serial No. 738,960.

For a detailed description of the present form of my invention, reference may be had to the following specification and to the accompanying drawing forming a part 5 thereof, wherein

Figure 1 is a plan of my device;

Fig. 2 a diametric section thereof;

Figs. 3 and 4 show details.

My invention resides in a former for 10 manufacturing rings of sheet metal from straight flat strips.

Referring to the drawing, A represents a die-block of cylindrical form with its bottom part shaped to be received in a vise 15 or otherwise mounted in a suitable standard. The upper corners of this block are shaped, as shown at *b b* Fig. 2, to conform to the molded outline of the ring which it is desired to produce. Fig. 4 shows an example 20 of such a ring. At one point in the periphery of the block is radially pivoted a grip-lever E. It is pivoted in a recess in the top face of the block and its upper surface is flush with said face and carries a 25 section of its molded corner at *b*. At the molded point the grip-lever is slightly thinner than the recess which contains it, leaving a small space G into which one end of the blank H may enter. The lever seats on a 30 smaller spring K which prevents sticking and gives a yielding upward pressure of the lever against the blank at the start of the shaping operation.

A rotating die-lever C is journaled centrally on the block by means of the bolt B. On one side of lever C is a recess R for the reception of the removable die-member D which is shaped on its under side to conform to the molded surface *b* of the die-block. 35 This die-member D is shown separately in Fig. 3, its rear end being formed to fit firmly yet easily in the socket on lever C formed by the aforesaid recess R. The molding or grooving on the under side of the die-member is widened out, as shown by dotted lines 40 in Fig. 2, to provide for the gradual entry of the blank into it.

The operation is as follows:—A blank H, shown by dotted lines in Fig. 1, and consisting 45 of a strip or ribbon of metal, has one end inserted in the space G beside the grip-

lever E which is then brought down to secure the strip. The strip is then bent over the top face of the lever and extends therefrom tangentially to the die-block as indicated in Fig. 1. Assuming the die-member D to be in place in its socket R on lever C, the lever will be rotated in a clockwise direction around bolt R until member D engages the downturned end of strip H. 55 Then, by the continued rotation of lever C, the strip will be bent and shaped between the two parts of the die, until it is of the form shown in Fig. 4 after a complete rotation of the lever.

What I claim as new and desire to secure by Letters Patent is:

1. A metal former of the character described comprising a die block having its top provided with an annular shaping surface, means forming part of said shaping surface for anchoring one end of a blank below the plane of said shaping surface, a die carrier mounted to travel over said shaping surface, and a die supported by said carrier and cooperating with said shaping surface. 70

2. A metal former of the character described comprising a die block having its top provided with an annular shaping surface, a grip lever pivoted to said block and having a portion of its upper surface constituting part of said shaping surface, a die carrier mounted to travel over said shaping surface, and a die supported by said carrier and cooperating with said shaping surface. 80

3. A metal former of the character described comprising a die block having its top provided with an annular surface having a transverse recess therein, a grip lever pivoted to said die block and extending through said recess, said lever being narrower in width than the recess and having a portion constituting a part of said shaping surface, a die carrier mounted to travel over said shaping surface, and a die supported by said carrier and cooperating with said shaping surface. 90

4. A metal former of the character described comprising a die block having its top provided with an annular shaping surface having a transverse recess therein, a 100

grip lever pivoted to said die block and extending through said recess, said lever having a portion forming a continuation of said shaping surface bridging the space formed by said recess, a spring yieldably supporting said lever, a die carrier mounted to travel over said shaping surface, and a die sup-

ported by said carrier and cooperating with said shaping surface.

Signed at New York city, county and ¹⁰ State of New York, this 19th day of September, 1924.

JOHN BIRO.
